ATTORNEY

UNITED STATES PATENT OFFICE.

THOMAS H. MUTH, OF PATERSON, NEW JERSEY.

PIPE-FLANGING TOOL.

Application filed September 26, 1924. Serial No. 740,006.

To all whom it may concern:

Be it known that I, THOMAS H. MUTH, a citizen of the United States, residing at Paterson, in the county of Passaic and State 5 of New Jersey, have invented certain new and useful Improvements in Pipe-Flanging Tools, of which the following is a specification.

The object of this invention is to provide 10 an efficient and simple hand implement whereby ductile pieces may be gaged for a swaging operation and then swaged, as pieces or lengths of copper tubing which require to have their ends swaged so as to 15 form them flanged or flaring. In carrying out my invention and in order to produce an implement of this character of practical value I have had in mind the following: That the implement should include provision 20 for first gaging the portion of the piece therein so as to determine the extent to which the swaging is carried, or in flanging a tube for example, the extent of its flange; that, while the piece is to be held by the 25 implement under slip-friction for the purpose of this gaging, it should be held positively while the swaging operation is being effected; that both for the gaging and swaging operations the implement in the best 30 form should include provision for guiding the gaging or swaging device, as the case may be; and that the implement should be constructed in sections so that when the 35 piece to be operated upon already has one end up-set or swaged it can be removed from the implement after the other end has been swaged.

In the accompanying drawing,

Fig. 1 is a vertical sectional view of the 40 implement, with a piece of tubing therein ready to be shifted to gaged position by the device shown in dotted lines, which is a combined gaging and swaging device;

Fig. 2 is a similar view showing the parts 45 after the gaging has been effected, said device being here shown in solid lines;

Fig. 3 is a view similar to Fig. 2 but showing the parts in the position after the 50 swaging operation has been effected;

Fig. 4 shows the holder in vertical section;

Fig. 5 is a plan of the holder;

Fig. 6 is a vertical sectional view of the die; and

Fig. 7 shows the swaged end portion of a 55 tube.

In the drawings, *a* is a shell which is here 60 formed cylindrical and open at both ends. One end is somewhat reduced and there is an inclined continuous shoulder *b* joining the two interior diameters of the shell. In the portion of the shell having the lesser interior diameter are tapped two opposite screws *c*. *d* is a sectional tubular die which has a head *d'* that snugly fits the larger 65 interior diameter of the shell and below the head an enlargement *d''* which fits the smaller diameter of the shell, the diameters of the head *d'* and enlargement *d''* being joined by a conical shoulder *d³* of the same 70 taper as the shoulder *b*; below the enlargement *d''* the die is preferably of less diameter than the lesser interior diameter of the shell. The upper or head end of the die 75 has a conical die or anvil surface *d⁴*. In the present case the die is made in only two sections, the die being divided for this purpose in planes extending radially outwardly from the passage *d⁵* of the die. The sections abut each other laterally in a zone near and 80 extending in the present case well down below the anvil surface *d⁴*, as at *d⁶*, when they are arranged in the shell, which closely encompasses the head portion of the die; but for the remaining portion of the die downward 85 the sections are spaced, as at *d⁷*, by beveling the adjoining faces of the die sections.

I prefer to form the gaging and swaging means in one piece, as a cylindrical block *e* 90 of metal having a gaging protuberance or head *e'* at one end and its other end *e²* formed conical. In its function as a swaging device it acts by impact, or as a hammer; hence I term it a hammer swaging device.

The implement is used as follows: The die sections being removed from the shell 95 they are made to embrace the piece of tubing or the like *f* to be swaged, which then occupies the passage *d⁵* of the die. Then 100 these assembled parts are placed in the shell as shown in Fig. 1. At this time the holder

formed by the die and shell grips the piece f with some slip friction, partly so that the piece will not fall out before it is gaged and so that in the gaging operation it will not under impact of the device e be shifted perhaps excessively into the die. The device e is then introduced into the holder, with the head e' presented to the piece f , and by impact with the latter or otherwise is caused to force the piece to the position shown in Fig. 2, or so that the device e will impinge against the end face of head d' of the die, which end forms a gaging surface d'' . This will leave the tubing f protruding somewhat from the die as shown in Fig. 2. The screws d are then turned in and act to distort or bend inward the lower portions of the sections of the die, i. e., where said sections are spaced by the beveling at d' , the upper portions of the sections being held at this time by the shell against radial movement (or practically without any spaces being produced between the surfaces at d''); this results in the lower portion of the die clamping the piece positively, and as the upper portions thereof are held by the shell against separating, or so that appreciable spaces are not thus formed between them, the swaging operation can be proceeded with without forming burrs on the flange produced in coincidence with the plane d'' . Next the device e is inverted and its conical end being inserted in the holder (Fig. 3) it is driven into the tube f , expanding its upper end against the die seat d'' . When the swaging operation is thus completed the screws c are released so that the die sections and swaged piece may be removed. In the present example the device e when used as a gage abuts for gaging against the die sections, and so if one section should stand a little higher than the other the gaging operation may be made to force them both down against the shoulder b so that they will be level when they are clamped by the screws c .

Having thus fully described my invention, what I claim as new and desire to secure by Letters Patent is:—

1. In a swaging implement, a passaged holder having means to grip substantially positively the piece to be swaged upon the latter being placed in the passage of said holder with one end projecting, said holder having an anvil surface arranged to support said end of the piece in the swaging and also a gaging abutment adapted to limit the gaging thrust of a gaging device to press against said end and force the piece into the holder before said means is made to positively grip the piece, in combination with such gaging device guided in said holder and movable against the gaging abutment.
2. A holder for a piece to be swaged including a containing shell, a sectional die therein adapted to receive and hold the

piece to be swaged with one end projecting from the die, and means, having operative engagement with the shell and die, to force the die into substantially positive gripping relation to the piece, the die having an anvil surface arranged to support said end of the piece in the swaging and also a gaging abutment adapted to limit the gaging thrust of a gaging device to press against said end and force the piece into the die before the die is acted upon by said means, in combination with such gaging device guided in the holder and movable against the gaging abutment.

3. In a swaging implement, the combination of a cylindrical shell having an interior shoulder facing one end of the shell, means in the shell to substantially positively grip the piece to be swaged including a passaged die arranged in the bore of the shell and resting against said shoulder and having an anvil surface and also a gaging abutment both facing said end of the shell, said piece being adapted to be arranged in the passage of the die with one end projecting beyond its anvil surface, and a gaging device guided in the shell and movable against the gaging abutment before said means is made to positively grip the piece.

4. A swaging holder including a passaged die having at one end of its passage and laterally thereof an anvil surface, said die being circumferentially complete in a zone near but having its continuity interrupted in a zone further removed from said surface, and means to exert clamping pressure on the die in the latter zone, whereby to cause the die in said latter zone to contract upon and clamp a piece placed in said passage for swaging.

5. In combination, a passaged die divided in planes lengthwise of and extending outwardly from the passage into sections, said die having at one end of its passage and laterally thereof an anvil surface and the sections abutting each other laterally in a zone near but being spaced from each other in a zone further removed from said surface, a shell confining the portions of each section in the first zone against radial movement, and means, having operative engagement with the shell and with the die in the second zone, to distort the die into clamping engagement with a piece placed in said passage for swaging.

6. In combination, a swaging holder including a passaged die having at one end of its passage and laterally thereof an anvil surface, said die being circumferentially complete in a zone near but having its continuity interrupted in a zone further removed from said surface, and means to exert clamping pressure on the die in the latter zone, whereby to cause the die in said latter zone to contract upon and clamp a piece

placed in said passage for swaging, and a swaging member guided in said holder lengthwise of the passage.

7. In combination, a swaging holder including a passaged die having at one end of its passage and laterally thereof an anvil surface, and means to hold against slippage

through the passage the piece placed therein to be swaged, and a swaging device guided in said holder lengthwise of the passage and independently of said piece. 10

In testimony whereof I affix my signature.

THOMAS H. MUTH.
